Patented Oct. 18, 1910.

UNITED STATES PATENT OFFICE.

DELOS HOLDEN, OF UPPER MONTCLAIR, NEW JERSEY, ASSIGNOR TO JOHN H. DALE
OF NEW YORK, N. Y.

CLUSTER-SOCKET.

973,199.

Specification of Letters Patent.

Patented Oct. 18, 1910.

Application filed March 16, 1908. Serial No. 421,563.

To all whom it may concern:

Be it known that I, DELOS HOLDEN, a citizen of the United States, residing at Upper Montclair, in the county of Essex and State 5 of New Jersey, have invented certain new and useful Improvements in Cluster-Sockets, of which the following is a full, clear, and exact description.

My invention relates to electric light fixtures of the type in which two or more lamps are supported in a group or cluster and in which current is supplied to the lamps by permanent conducting elements which form a part of the structure of the 15 fixture, and which are adapted to receive current from a pair of line wires and supply the same directly to the individual lamp sockets. Clusters of this type are generally known as wireless clusters or cluster sockets, as distinguished from wired fixtures or clusters. In prior clusters it has been common to mount the threaded shells of the lamp sockets upon a conducting plate, said plate serving to rigidly secure the said shells together and to supply current thereto.

My invention has for its object the elimination of a plate of this character, the threaded shells being secured directly to one or more insulators which are in turn secured 30 to a rigid central conducting base which is electrically connected to the center contacts of the lamp sockets. The threaded shells being thus mechanically united, current may be supplied thereto by flexible conductors 35 brought to a common point to which the line wire may be connected. The insulation in this structure is preferably although not necessarily reduced to small separate elements interposed between the shells and central conductor.

In order that the invention may be more fully understood, reference is made to the accompanying drawing, of which—

Figure 1 is a plan view of a cluster constructed in accordance with my invention, the top plate being removed to expose the interior of the cluster; Fig. 2 is a section on line 2—2 of Fig. 1 showing the top plate in position; Fig. 3 is a perspective view 50 showing the rigid central conducting base to which the insulators and threaded shells are secured; Fig. 4 is a detail perspective view of one form of threaded shell which

may be used; and Fig. 5 is a similar view of one of the disks or buttons for insulating 55 the threaded shell from the central base.

In the cluster shown, the central conducting base is in the form of a rigid ring 1 of circular cross-section, said ring being preferably of brass or other metal. This ring is 60 drilled and tapped as shown at 2 to receive the screws 3, of which there is one for each lamp socket, and which are of metal, and act as the center contacts for the lamp sockets, and also as means for securing the 65 threaded shells in position. Upon each of the screws 3, and secured by the head thereof, is a washer 7, preferably of brass, a disk 6 of mica or other insulating material, an insulating disk or button 4, which may be of 70 porcelain or other suitable material, and a cup-shaped threaded shell 5, the bottom of which is cut out as shown in Fig. 4 to form a flexible tongue 8, and flanges 9. The flanges 9 are situated between the insulating disks 6 75 and 4, and the washer 7 is of greater diameter than the space between the said flanges. The parts being thus assembled upon the screw 3, the latter is inserted within the bore 2 and screwed firmly into position, 80 thereby rigidly fastening together the various parts which have been described and forming the structure shown in Fig. 3.

Any suitable means may be provided for electrically connecting the shells 5, but in 85 the cluster shown, the flexible tongues 8 are brought together at a central point and united by a metallic bushing 10, the ends of which are upset so as to bind the tongues tightly together, and the bore of the bushing 90 is tapped to receive a binding screw 11, for securing one of the line wires which enters the cluster through the conduit or pipe 12. A binding screw 13 is threaded in the ring 1 for receiving the other line wire 95 for supplying current to the center contacts of the sockets.

Any desired means may be employed for supporting the unitary structure shown in Fig. 3, but I prefer to support the same by 100 means of a cover removably applied to the top plate 17, said cover being shown as a hemispherical shell 14, preferably of brass, and provided with a plurality of pins 15, which engage slots 16, formed in the depending 105 flange of the top plate 17, and form bayonet

joints which permit the ready removal of the cover from the top plate. Insulating bushings 18 of porcelain or other suitable material are threaded upon the exterior of the shells 5, and the flanges formed on said bushings bear against the edges of the openings in the cover 14 and draw the cover and threaded shells into a rigid structure.

In carrying out my invention it is not necessary that the threaded shells be united to the ring 1 by engagement of a washer 7 with flanges 9, since the shell may be secured to the insulating disk 4 by any other means, as, for instance by screws or bolts passing through the flanges 9 and the disks 4.

Having now described my invention, what I claim, is:

1. In a cluster socket, the combination of a rigid metallic base, and a plurality of insulating blocks, threaded shells and center contacts carried thereby, the center contact for each shell being in electrical connection with said base.

2. In a cluster socket, the combination with a horizontal, rigid, metallic base, of a plurality of insulating blocks having inclined outer faces, threaded shells upon said inclined surfaces, and center contacts, all carried by said base, the center contacts for

each shell being in electrical connection with said base.

3. In a cluster socket, the combination of a rigid metallic base, a plurality of insulating blocks and threaded shells, and center bolts for clamping said members together, said bolts being electrically connected to the base and forming the center contacts of the lamp sockets.

4. In a cluster socket, the combination of a rigid metallic ring, and a plurality of insulating blocks, threaded shells and center contacts carried thereby, the center contact for each shell being in electrical connection with said ring.

5. In a cluster socket, the combination of a rigid metallic ring, a plurality of insulating blocks and threaded shells, and center bolts for clamping said members together, said bolts being electrically connected to the ring and forming the center contacts of the lamp sockets.

In witness whereof, I subscribe my signature, in the presence of two witnesses.

DELOS HOLDEN.

Witnesses:

FRANK S. OBER,

WALDO M. CHAPIN.
